UNITED STATES PATENT OFFICE

ARTHUR G. MESS, OF DAYTON, OHIO, ASSIGNOR TO THE NATIONAL REGISTER COMPANY, OF DAYTON, OHIO, A CORPORATION OF MARYLAND

DESIGN FOR A BOOK END

Application filed February 13, 1932. Serial 42,853. Term of patent $3\frac{1}{2}$ years.

To all whom it may concern:

Be it known that I, ARTHUR G. MESS, a citizen of the United States, residing at Oakwood, Dayton, Ohio, in the county of Montgomery and State of Ohio, have invented a new, original, and ornamental Design for Book Ends, of which the following is a specification, reference being had to the accompanying drawings, forming part thereof, in which—

Fig. 1 is a view of the front of the book end showing my new design.

Fig. 2 is a perspective view showing the front and right side of the book end.

Fig. 3 is a perspective view showing the front and left side of the book end.

The design is characterized by a represen-

tation, in relief, of the head of an elephant with extended ears and trunk, said representation being mounted on the forward or end face of the book end. The end face has a gradual incline while the side faces have relatively sharp inclines. All three faces are provided with a modeled surface outlined with a plan raised border. A plate or marker tablet is shown on the inclined front end face, but it may be used or omitted as desired.

What is claimed is:

The ornamental design for a book end, as shown and described.

In testimony whereof I affix my signature.

ARTHUR G. MESS.
